UNITED STATES PATENT OFFICE.

CHARLES D. YOUNG, OF COLUMBUS, OHIO, ASSIGNOR, BY MESNE ASSIGNMENTS, TO
AMERICAN STEAM GAUGE & VALVE MANUFACTURING COMPANY, OF BOSTON,
MASSACHUSETTS, A CORPORATION OF MASSACHUSETTS.

PRESSURE-RECORDER.

1,265,156.

Specification of Letters Patent.

Patented May 7, 1918.

Application filed July 6, 1909, Serial No. 506,172. Renewed July 20, 1915. Serial No. 41,020.

To all whom it may concern:

Be it known that I, CHARLES D. YOUNG, a citizen of the United States, residing at Columbus, in the county of Franklin and 5 State of Ohio, have invented a certain new and useful Improvement in Pressure-Recorders, of which the following is a specification.

The primary object of this invention is to 10 provide an improved and convenient means for obtaining a graphical diagram of the hydraulic pressure at each movement of the piston of a hydraulic press in mounting wheels on axles, but the invention can be 15 used for other purposes and with other fluid pressures or other stresses.

The invention resides in the construction 20 of the parts of the instrument, as herein shown and described and then particularly 25 pointed out in the claims.

In the accompanying drawings in which I have illustrated the embodiments of the invention and its application in use:

Figure 1 is a plan or top view with the 25 interior mechanism shown in broken lines under the cover;

Fig. 2 is a view in elevation of the front 30 side of the case as shown in Fig. 1, the interior parts being shown in broken lines;

Fig. 3 is a horizontal sectional view of the 35 line $x-x$ of Fig. 2;

Fig. 4 is a view in elevation of the right 40 hand end of the case with the interior parts shown in broken lines;

Fig. 5 is a view showing the instrument 45 attached to a hydraulic wheel-press used for applying or removing wheels to or from axles;

Fig. 6 is a sectional detail of the indicator.

Fig. 7 is a section on the line $y-y$ Fig. 3 50 looking down.

Fig. 8 is a section on the same line $y-y$ looking up.

Fig. 9 is a detail view of the interior 55 spring pawl that engages the tape winding roll.

In the views 7 designates the case which is of suitable form and capacity to receive the operating parts and having a top or 60 cover hinged thereto at 7^a , and a sliding bottom 7^b . When the top and bottom are in closed position they are locked by means of a bolt 7^c passed through suitable holes in both, said bolt being provided with an eye

7^d through which a seal or other secure lock 55 is passed to prevent access of the workman to the parts within the box, it being a feature of my invention to provide a construction secure against unwarranted manipulation or forgery of the records. In railroad 60 practice it is important that those in authority be apprised of defects in car wheels. The rear side of the case 7 is provided with a large opening 7^e through which the drum and tape can be removed, and the cover is 65 provided with a slotted tongue 7^f to embrace the shank of the drum of that mechanism.

The devices within the case are as follows: A paper tape roll receiving spindle 8 mounted in suitable bearings, one of which, 8^a is 70 yielding, so that the spindle can be easily inserted and removed. The bearing also provides tension to prevent the spindle from turning too easily. The spindle has secured to it a longitudinally arranged spring clip 75 8^b that is free at one end so that the inner end of the paper tape can be slid under it and be held to keep the roll from turning on the spindle. A drum 9 to unwind the tape from the roll on the spindle 8. The 80 drum 9 has a mechanism for imparting to it an intermittent movement in one direction only, consisting of an external head 10 having a toothed rim engaged by diametrically opposite spring pressed paws 10^a. The head 85 10 is secured in the case by a set screw 12 engaging a groove in the head and so as to permit the head to turn. The drum 9 is removably attached to this head 10 so as to be turned with it and the pawls 10^a prevent a return movement of the head or drum after it has wound the paper strip onto itself. The drum 9 and head 10 are intermittently rotated by an internal head 11 provided with a grooved end 11^a to receive 90 a cord 11^b that extends to the exterior of the case and spring pressed pawls 11^c carried by the internal head that engages a circular rack 11^d on the head 10. The drum 9 has within it an axial stationary rod 9^a on which 100 is secured a spring 9^b which is also secured to the internal head 11 so as to tend to restore that head by rotation to a given position when pulled out of it by the cord 11^b.

The rod 9^a is secured in proper position in 105 the case by a thumb nut 15 on the exterior of the case. The spindle 8 and drum 9 are located parallel to each other with a space

between them and in this space is arranged and secured near the cover a platform or tablet 13^b over which the tape passes from the spindle to the drum, the latter being provided with a slot 9^c through which the free end of the tape is inserted to initially bind the tape to that member. The tablet or platform is flanked with anti-friction roller 13^a to facilitate the passage of the tape onto and off it. The cover is provided with a glass pane 14 through which the operation of the marker can be observed, but a small portion of the cover is left open at the rear end of the pane, as seen at 14^a, to expose the edge of the tape for memoranda on the part of the operator or for identifying the several articles treated with the corresponding records made by the instrument.

The indicator shown in detail in Fig. 6 and designated generally by the character 16 is substantially the same as that now commonly used in devices of the class to which the present invention belongs. It has the usual straight line motion stylographic pen arm 16^a to the end of which is secured a small stylographic pen or other suitable devices 16^b for marking and suitable means for securing proper pressure of the marking device on the paper tape. The arm is operated by pressure on a suitable piston stem 16^c both working in suitable casing 16^a but in the present instance the casing is made with a vent 16^e to release pressure should that become excessive, and the pen is held in zero position by means of a spring 16^f acting on the piston stem.

Referring more particularly to Fig. 5 in which my invention is shown as applied to a hydraulic press for pressing car wheels onto an axle, the character 17 designates the hydraulic pressure cylinder and 18 the rod of the piston working therein. The instrument, as a whole, is communicably connected with the hydraulic cylinder by suitably connecting the casing 16 of the indicator with the chamber of the hydraulic cylinder, as usual or so that pressure in the cylinder is communicated to the indicator. The instrument is arranged with the tape in a horizontal position as being most convenient for the inscription of the memoranda upon the exposed part thereof. The cord 11^b, hereinbefore referred to is attached to a small wheel 19 which is fixed on a shaft 20 having another larger wheel or pulley 21 on which is another cord 21^a attached to the piston rod 18 so that as said rod is moved inward under the action of pressure it winds up the cord 11^b and therefore moves the paper tape. The same pressure that moves the rod also, of course, moves the indicator and marker thereby describing on the tape a curve corresponding to the pressure exerted, as usual, generally in such devices. When the pres-

sure is cut off, the piston of the hydraulic cylinder is returned to initial position by means of a weighted chain 22 attached to the piston to draw it in the proper direction. The return of the piston under the action of the weighted chain can be speeded by opening a suitable cock to permit the discharge of the water or pressure fluid from the cylinder. In the return of the piston the cord 11^b is, of course, rewound on the number 11 by the reaction of the spring 9^b.

What I claim and desire to secure by Letters Patent is:

1. In a pressure recorder, in combination, a case for containing a paper tape and means for supporting and means for moving the tape, a movable marking device and means for moving the same, the means for moving the tape and the marking device being actuated by the same source of pressure or stress, said case being constructed to prevent unauthorized access of the attendant to the marking device and provided with an aperture to expose a portion only of the tape beyond the zone of operation of the marking device for the inscription of memoranda thereon by the attendant.

2. In a pressure recorder in combination, a case, a paper tape with means for intermittently moving the same and a stationary platform or tablet over which the tape passes mounted in the case, a movable marking device to mark on said paper tape where it passes over the platform or tablet, the means for moving the paper tape and the marking device being operative independently of each other, a common source of pressure or stress for operating both the marking device and the paper tape, said case constructed to prevent unauthorized access of the attendant to the marking device and provided with an aperture to permit the inscription of memoranda on the tape.

3. In a pressure recording apparatus, the combination of a pressure-actuated marker, means for moving said marker, a record roll holder having trunnions at its ends, bearings for mounting said holder, in which said trunnions are adapted to rotate, one of which bearings is yielding axially so that the holder may be removed, means for pressing said movable bearing toward the drum, means for preventing rotation of said bearing, a winding drum, and means for turning said drum to draw the record strip from the roll holder and wind it on the drum, the strip in passing from the holder to the drum being carried past and in contact with the marker.

4. In a pressure recording apparatus, the combination of a pressure-actuated marker, means for moving said marker, a record roll holder, a winding drum on which the record strip is wound and by which it is drawn from the holder past the marker and in con-

tact therewith, a toothed head to which the drum is removably attached, and an oscillating internal head having means for engaging the first drum and turning it intermittently when turning in one direction.

5. In a pressure recorder, the combination with a case, of a record sheet and a support therefor within the case, a pressure actuated marker also within the case arranged to bear 10 on the record sheet, mechanism operable by fluid pressures and connected with said marker for moving the same through distances proportional to such pressures, and means for moving the record sheet past the 15 marker, the case being closed against unauthorized access of workmen to the marking device, and having a transparent portion over the path of movement of the marking device, through which the action of said 20 device may be observed, and having also an aperture located so as to expose a portion of

the record sheet near the path of the marker to permit the inscription of memoranda on the sheet.

6. A pressure recorder comprising in combination a record member, a marker arranged to mark upon said record member, pressure controlled means for moving said marker in response to changes in pressure of the fluid of which the pressures are to be recorded, a case inclosing the operative elements of said recorder and having means to prevent unauthorized access of an attendant to said operative elements, and said case having means permitting the attendant to complete or supplement the record made by said marker. 25 30 35
